US00D606578S

(12) **United States Design Patent**
Markovitz et al.

(10) **Patent No.:** **US D606,578 S**
(45) **Date of Patent:** **** Dec. 22, 2009**

(54) **EYEGLASSES**

(76) Inventors: **Aaron Markovitz**, 2361 Mason Ave.,
Suite 100, Daytona Beach, FL (US)
32117; **Artiss Akarra**, 2361 Mason
Ave., Suite 100, Daytona Beach, FL (US)
32117

(**) Term: **14 Years**

(21) Appl. No.: **29/312,420**

(22) Filed: **Oct. 17, 2008**

(51) **LOC (9) Cl.** **16-06**

(52) **U.S. Cl.** **D16/320; D16/326**

(58) **Field of Classification Search** D16/101,
D16/300-342; D29/109-110; D24/110.2;
351/41, 44, 51-52, 62, 158, 92, 103-123,
351/140, 153, 45-46; 2/426-432, 447-449,
2/441, 434-437, 13, 15; D21/483, 659-661

See application file for complete search history.

(57) **CLAIM**

The ornamental design for eyeglasses, as shown and described.

DESCRIPTION

FIG. 1 is a top view illustrating my design for eyeglasses;
FIG. 2 is a perspective view thereof;
FIG. 3 is a side view thereof;
FIG. 4 is a front view thereof;
FIG. 5 is a bottom view thereof; and,
FIG. 6 is a rear view thereof.
